SINTERING APPARATUS

Henry J. Stehli, Cedar Grove, N. J.

Application October 25, 1938, Serial No. 236,840

9 Claims. (Cl. 266—21)

My invention relates to sintering apparatus, both to machines of the Dwight & Lloyd continuous type, and to the intermittent or pan type.

Sintering machines of the continuous type consist of a suction box or a series of suction boxes over which pass pallets or cars having a pervious bottom and filled with a charge of ore. The pallets or cars make very close contact with the top of the suction boxes to form an air seal, the effect of the suction being to draw the cars or pallets downwardly onto the edge of the suction boxes to form an effective seal. The charge of ore in the cars is combustible or is admixed with a fuel and, upon being ignited at the top surface as it passes over the suction boxes, the down draft of air causes the charge of material on the pallets or cars to burn progressively downwardly from the top to the bottom of the charge.

The pan type sintering apparatus consists of a pot or pan provided with a grate bottom and having an exhaust box underneath the grate. In operation, the charge is placed on the grates, levelled off and ignited at the top surface, and air is drawn through the bed to burn the fuel as in the continuous type.

In the operation of sintering apparatus, the gases passing into the suction box are hot and generally full of dust, acid constituents and, sometimes, sublimed sulphur, volatilized metals or metallic oxides, or other corrosive materials, depending upon the charge on the apparatus. These hot gases are, therefore, very destructive to the blowers and it has therefore been necessary to use fans of the centrifugal type having wide clearances and low mechanical efficiencies. Under certain conditions as, for example, when chlorine gas is liberated during the roasting or sintering, such centrifugal fans are rapidly attacked unless built of expensive material such as corrosion resistant alloys. In the above types of sintering apparatus the amount of suction or pressure difference between the top and bottom of the charge is limited. For example, it is difficult to obtain a vacuum much greater than 20 inches of water, due to cost, and there is generally an upper limit to the vacuum of about 28 inches of water.

Efforts have been made to overcome these limitations by supplying air under pressure to the top of the sintering machine and thereby to run the machine under pressure rather than under vacuum. For this purpose it has been proposed to provide a pressure hood above the sintering machine and fitting tightly on the upper edges of the moving cars or pallets. Although this avoids the necessity of passing hot gases through fans or

blowers or exhausters, other difficulties have been encountered which have proven substantial obstacles to the successful operation of the machine.

Among these difficulties is that of making a satisfactory seal joint between the cars or pallets and the pressure wind box or hood above the machine. To provide a seal with a wind box, it is necessary to have cross partitions at each end of the cars or pallets to make an end seal as well as to seal the sides of the cars to the wind box. These cross partitions interfere with the even feeding of the cars and must be swept free from the charging material in order to form a tight seal and are subject to rapid destruction by the flame of the ignition burner and also to warping from the effect of heat. The effectiveness of the seals is, therefore, subject to impairment due to the above and other causes. The pressure hood or wind box also serves to prevent access being had to the material being sintered so that if local conditions interfere with proper sintering as, for example, if blow holes develop, they cannot be quickly detected and plugged.

In my present invention I avoid all of the above difficulties of the suction and wind box arrangements and provide a sintering apparatus in which air for combustion may be supplied under pressure, thereby avoiding the necessity of handling or exhausting hot exhaust gases, and in which a pressure differential through the sintering bed of any desired magnitude may be maintained, and in which the sintering bed is open and accessible to the operator.

In my invention I enclose the sintering apparatus, or a number of sintering apparatus, each of which is provided with a collection or exhaust box or system similar to the suction boxes heretofore used, in a room or structure maintained under air pressure. The pressure of the exhaust gases leaving the sintering apparatus may be either at atmospheric pressure or slightly above or below atmospheric pressure, depending upon the stack conditions if the exhaust gases pass directly to a stack, or upon the conditions in the treating apparatus if the gases are subjected to further treatment. Air under suitable pressure is continuously supplied to the room or enclosure within which the sintering apparatus is operated. Ore or other charging material is also continuously supplied and distributed on the upper surface of the charge holders. The ore material is ignited from a burner, or other suitable means, in its initial passage or entrance over the exhaust boxes and thereafter downward combustion is maintained by the air under pressure passing

downwardly through the ore charges to the off-take or exhaust boxes. The sintered material discharged from the sintering apparatus is then taken from the enclosure or room by a water seal, 5 air lock or other discharge means. Air may be supplied to the building or structure under any suitable pressure to maintain the proper draft. A pressure of 2 to 3 pounds per square inch will usually be the maximum required. The operators 10 for running the sintering apparatus may, therefore, be within the enclosure or room inasmuch as this pressure will cause no substantial discomfort.

The various features of the invention are illustrated in the accompanying drawing, in which—

15 Fig. 1 is a diagrammatic vertical section of a continuous sintering apparatus embodying my invention.

Fig. 2 is a similar section of a part of a sintering apparatus embodying a different arrangement 20 of the section box.

In the apparatus shown in Fig. 1, a sintering machine, comprising a chain of pallets or cars 10 passing between pairs of supporting wheels 11 and 12, is positioned within a room or enclosure

25 13. In its upper flight the chain of pallets passes over and is supported on the structure of an exhaust box 14 having an outlet or exhaust flue 15 leading to a stack 16 outside of the enclosure 13. Air under pressure is supplied to the en-

closure or room 13 by means of a blower 17 which delivers through a delivery pipe 18 into the enclosure 13. The air under pressure thus supplied to the enclosure 13 passes downwardly through the upper flight of cars or pallets into 35 the exhaust box 14, as indicated by the arrows, and thence into the exhaust flue 15 leading to the stack 16.

The material to be sintered as, for example, ores, ore concentrates, fuel, colloids or other re- 40 agents, may be supplied from one or more bins 19 by means of automatic feeders 20 to a common conveyor 21 and thence delivered to an open ended hopper 23 mounted in the roof of the building 13, and having its lower end within the building. The material is fed from the lower end of 45 the hopper 22 by means of an automatic feeder 23 driven by a belt or other transmission 24 from the driving wheel 11 of the sintering machine. This ensures a speed proportionate to the speed 50 of the sintering machine. The feed, however, may be regulated by means of a control gate 25. The mass of material in the hopper is generally sufficient to seal the room against undue loss of air but if not a suitable sealing device may be pro- 55 vided.

The material from the hopper 23 passes into a mixer or pelletizer 26 from whence it is delivered to a feed hopper 27 at the front end of the sintering machine and by which it is spread in an even 60 bed onto the traveling pallets or cars. The material thus spread onto the pallets passes beneath a burner 28 where it is ignited and, in its further passage over the exhaust box 14, is burned in a descending zone until it is completely sintered.

65 As the pallets pass over the wheels 12 at the delivery end of the sintering machine, they drop the sintered material into a water seal 29 from which it may be lifted by a bucket or other type of conveyor 30 outside of the building and de- 70 livered into a car 31, or other receptacle.

The wall of the building 13 extends into the water seal 29, as at 32, to maintain the seal while permitting the sintered material to pass therethrough.

75 In the modification shown in Fig. 2, the ex-

haust box 14 is provided with partitions 33 which divide the exhaust box into a number of separate chambers 34. The chambers immediately below the ignition burner 28 exhaust through a pipe 35, the chambers in the central part exhaust through a pipe 36, and the end chambers exhaust through a pipe 37. This permits separate treatment of the different gases. For example, the gases being exhausted through the pipe 36 from the central part of the sintering apparatus may be rich in 10 sulphur dioxide and, therefore, useful directly for acid making. The gases passing through the exhaust pipe 35, from immediately beneath the ignition burners, may contain gases unsuitable directly for the making of acid, and may be 15 treated specially. The gases passing through the exhaust pipe 37 may be free of any useless or deleterious materials and may, therefore, be exhausted directly to the atmosphere. It will be understood, of course, that the particular treatment of the exhaust gases may vary.

It will be understood that the illustration in the drawing is merely by way of example, and that any suitable enclosure may be employed, either about each individual sintering machine or, 25 if more than one sintering machine is in operation at a time, a single enclosure may be employed for several such machines.

Through the above invention I am able to maintain a relatively high air pressure on the material being sintered and avoid the difficulties of maintaining an air tight seal between the traveling pallets and the pressure hood. Inasmuch as the air is supplied while cool, dense and free from dust and corrosive materials, efficient blowers 35 such as Turbo blowers, rotary blowers, or other positive pressure blowers having slight clearance spaces and high mechanical efficiencies may be employed. Moreover, as the air is blown into the building in large quantities and thence passes 40 into and through the sintering machine, it tends to clear the atmosphere within the building or enclosure of dust, fumes, etc., which are carried into and through the sintering bed. This makes working conditions about the sintering machine 45 much better than would be the case if a pressure hood or a suction apparatus were employed.

In my invention it will also be noted that by partitioning the exhaust boxes, gases of different qualities may be withdrawn from the different 50 parts of the sintering machine without requiring a fan or exhauster for each gas withdrawn.

What I claim is:

1. Sintering apparatus which comprises a sintering machine having successive moving pallets 55 for supporting a bed of material to be sintered, an exhaust box below and sealed to the pallets of said sintering machine, a room enclosing said sintering machine, and means to supply air under pressure to said room.

2. Sintering apparatus which comprises a sintering machine having successive moving pallets to support material to be sintered, means to ignite the material on said pallets, an exhaust box 65 having a number of partitions dividing it into separate compartments, a room enclosing said sintering machine, and means to supply air under pressure to said room.

3. Sintering apparatus which comprises a sintering machine having successive moving pallets to support material to be sintered, means to ignite the material on said pallets, an exhaust box below and sealed to said pallets, said exhaust box having a number of partitions dividing it into sep- 75

arate compartments, a room enclosing said sintering machine, means to supply air under pressure to said room, and means to supply sintering material to said room.

7. Sintering apparatus which comprises a sintering machine having successive moving pallets to support material to be sintered, means to ignite the material on said pallets, an exhaust box below and sealed to said pallets, said exhaust box having a number of partitions dividing it into separate compartments, a room enclosing said sintering machine, means to supply air under pressure to said room, means to supply sintering material to said room and to said sintering machine therein, and means to withdraw sintering material from said room.

8. A process of sintering material which comprises supplying said materials to a room under super-atmospheric pressure, spreading said material in a layer in said room and continuously passing said layer over an exhaust chamber at a lesser pressure than that of said room, igniting said layer as it passes over said exhaust chamber and burning it with a down draft of air.

9. A process of sintering material which comprises supplying said materials to a room under super-atmospheric pressure, spreading said material in a layer in said room and continuously passing said layer over an exhaust chamber at a lesser pressure than that of said room, igniting said layer as it passes over said exhaust chamber and burning it with a down draft of air, and separating the exhaust gases in said chamber into separate streams at successive distances in its path of travel.

HENRY J. STEHLI.

5. 4. Sintering apparatus which comprises a sintering machine having successive moving pallets to support material to be sintered, means to ignite the material on said pallets, an exhaust box below and sealed to said pallets, said exhaust

10 box having a number of partitions dividing it into separate compartments, a room enclosing said sintering machine, means to supply air under pressure to said room, means to supply sintering material to said room and to said sintering machine therein, and means to withdraw sintering material from said room.

5. Sintering apparatus which comprises a sintering machine having successive moving pallets to support material to be sintered, means to ignite the material on said pallets, an exhaust box below and sealed to said pallets, said exhaust box having a number of partitions dividing it into separate compartments, a room enclosing said sintering machine, means to supply air under pressure to said room, and a water seal into which sintered material is delivered and from which it may be withdrawn outside of said room.

6. Sintering apparatus which comprises a room, a sintering machine in said room, said sintering machine having continuous moving means to support material to be sintered, an exhaust box below said means, means for sup-
